G. D. SHIELDS

ROTARY DRILLING AND REAMING TOOL ORGANIZATION

Filed Feb. 23, 1927

UNITED STATES PATENT OFFICE.

GEORGE D. SHIELDS, OF LOS ANGELES, CALIFORNIA, ASSIGNOR OF ONE-FOURTH TO
BERT RUSSELL, OF SOUTH PASADENA, CALIFORNIA.

ROTARY DRILLING AND REAMING TOOL ORGANIZATION.

Application filed February 23, 1927. Serial No. 170,121.

My present invention relates to a drilling organization which may include an ordinary fish-tail or other terminal bit, which I term a pilot bit, with which I employ a hollow shaft, through which a usual lubricating liquid may be delivered to said terminal or pilot bit, for the carrying of a reaming element or elements; and it is a particular advantage of the organization here referred to that, all parts being rigidly interconnected in use, and means being provided not only for the substitution of any desired reaming elements but for the spacing of the same at any desired intervals, rotation may be transmitted thereto and therebetween by clutch-like faces provided thereon,—a bottom stop or clamping element being preferably provided with a face suitable for cooperation with any desired reaming and/or mudding 10 and/or burnishing or straightening element or elements, as hereinafter described.

It is an object of my invention to provide, for use in an organization of the general character referred to, a graduated series of 15 reaming elements, these being preferably so disposed relatively to one another and to a terminal or pilot bit as to assure the comparatively easy cutting of a relatively straight hole—unitary or one-piece annular 20 reaming elements comprising hollow hubs being respectively provided with radially extending teeth whose edges (whether straight or curved or downwardly tapered) lie in vertical planes and are equally spaced 25 and favorably disposed both for a cutting effect and for the upward circulation of a lubricating liquid; and, in preferred embodiments of my invention, some or all of the reaming elements referred to (and also 30 spacing and/or burnishing or other wall-perfecting elements interchangeable therewith) may be provided with “mudding” 35 vanes of less diameter than the maximum diameter of the well hole, comprising rearwardly inclined and rounded or other surfaces favorably disposed for a centrifugal or pressure effect in the coating of a reamed hole with mud,—to prevent caving and/or 40 to exclude water, or the like, during continued drilling operations.

It will be understood that these mudding vanes, being of less diameter than the well hole and designed to have a centrifugal effect upon the mud will cause the wall to

be plastered without the attending crumbling of soft formation which would accompany a vane that “rubbed” the mud into the wall. I have, further, found that I obtain a greater depth of impregnation of mud into the wall through the mentioned centrifugal action than is possible with a fin having a diameter equal to the diameter of the hole.

Other objects of my invention, which essentially includes a reaming or hole-perfecting organization suitable for interposition in a rotary drill string in such manner as to afford guidance for a terminal or pilot bit and favorably to distribute the cutting effort, assuring rapid cutting, minimum wear and a practically straight hole, may be best appreciated from the following description of an illustrative embodiment of said invention, taken in connection with the appended claims and the accompanying drawings, in which

Fig. 1 may be referred to as an elevational half-section, showing an embodiment of my invention within a well hole cut thereby,—parts being broken away.

Fig. 2 is a horizontal sectional view, taken substantially as indicated by the line 2—2 of Fig. 1.

Fig. 3 is an elevational view of a preferred type of spacer,—such as may be substituted for any one of the reaming elements shown in Fig. 1.

Fig. 4 is an elevational view of a preferred type of burnishing element optionally to be used, in place of one of the reaming elements shown in Fig. 1, or in addition thereto, for a straightening and/or smoothing effect upon the interior of a well hole, or upon a casing therein.

Referring to the details of that specific embodiment of my invention chosen for purposes of illustration, I show a hollow shaft 11 as upwardly terminating in a so-called “pin” 12,—which may be such as is ordinarily provided upon rotary drill tools; and the lower end of this shaft is accordingly provided with a so-called “box” 13,—so that the shaft 11, providing an interior passage 14 for the downward delivery of a lubricating liquid, may be interposed at any desired level, in a rotary drill string, above a fish-tail or other terminal or pilot bit 14'.

The illustrated bit 14' is shown as pro-

vided with a pin 15, entering a box 16 in a "sub" or section 17; but it should be understood that, if desired, the pin 15 may be inserted directly in the box 13,—guidance 6 being then presumably secured by elongating the shaft 11, or by the use of a plurality of such shafts having reamers, or equivalent elements, suitably spaced thereon.

I show the shaft 11 as provided with a 16 lower stop or clamping element 18 (which may be threaded or welded or otherwise rigidly secured thereon) the upper surface of this cylindrical stop element being provided with a clutch-like face,—produced by 15 cutting a series of uniform notches or depressions 19 therein, for engagement by corresponding projections upon the unitary and annular bodies or reaming elements, or the like, of any desired character.

20 In Fig. 1, I show a graduated and equally spaced series of reaming elements 20, 21, 22 and 23 as each comprising a substantially cylindrical body or hub, downwardly and upwardly terminating in a clutch-like face,— 25 equally spaced projections 24 upon the lowermost reaming element 20 being shown as interfitted within the mentioned notches 19 in the stop element 18. Similarly, all of the mentioned reaming elements being preferably of the same standard length, and all (or, all but the uppermost) being provided with two clutch-like faces interfitting in the described manner, and suitably to the transmission of a torque from a lower reaming 30 element to an upper reaming element, I show the uppermost reaming element 23 as retained by a stop or clamping element in the form of a nut or interiorly threaded collar 25 (preferably provided with a left-hand thread); and although, in case a graduated 35 series of reaming elements is employed, said elements may be provided with either like or different cutting edges, I show the lowermost reaming element 20 and an intermediate reaming element 22 as provided with straight but downwardly convergent edges, disposed in radial vertical planes (and optionally reinforced by stellite or other facings, substantially as shown at 26, Fig. 2) 40 whereas the uppermost reaming element 23 is shown as provided with straight and vertical cutting edges, without taper; and the intermediate reaming element 21 is shown as provided with oppositely tapering 45 or rounded-profile cutting edges or teeth; but I may, in any case, provide the teeth of my reamers, teeth of each reamer being disposed in a common transverse plane, with flat and radial forward faces (as best shown 50 at 27, Fig. 2) and with rounded rearward faces 28; and, in order that said reaming elements may serve not only for the enlargement of a hole but for a "mudding-up" 55 effect (to prevent caving or undesired entrance of water) I may in some or all cases 60

provide each of the cylindrical bodies of my reamers with "mudding" vanes such as are shown in profile at 29, 31 and 32 in Fig. 1, and, in plan, in Fig. 2,—the forward surfaces of these vanes (one or any desired 70 plurality thereof being provided upon a reamer) being rearwardly inclined, at the outer ends thereof, in a manner favorable to the throwing or pressing of mud toward the wall of a hole,—and the uppermost vane 75 or face being preferably of less diameter than the cutting section of the reamer carrying the same.

When I desire to use but one reamer, of a less number than that to which the interval between stops 18 and 25 may be adapted, I may substitute, for any number of reamers shown, a spacing element or elements of the general character shown at 33 in Fig. 3— 80 this element being provided with clutch-like faces such as are shown at 34 and 35 and optionally also with one or more "mudding" vanes 36. Although the use of the described organization is intended to precede or obviate the installation of a casing within 85 a well hole, it should be noted that, upon reversing the position of a reaming element of the general character shown at 21, so that what then becomes the advance faces of the teeth thereof are backwardly inclined with reference to radial planes, or by the employment of a burnishing or other rounded element such as is separately shown at 37 in Fig. 4, (this annulus having an uninterrupted peripheral surface) I may utilize an 90 organization of the general character described (optionally foregoing all use of cutting elements therewith) in straightening or smoothing out any irregularities in a well 95 casing or in the interior of a well hole; and the backward inclination of teeth such as are shown on the annular reaming element 21, assuming said element to be turned end for end upon the hollow shaft 11, may also 100 be very advantageously used in the "side-tracking" of a hole,—as for the purpose of passing a "fish". In reaming a preformed 105 hole, obviously any terminal guide of suitable diameter may be substituted for the terminal bit 14'. 110

115 The general mode of operation of my combination rotary drilling and reaming organization having been clearly indicated above, I emphasize (1) the fact that said organization permits the use of a comparatively small terminal or pilot drill bit even in the cutting of a comparatively wide hole; (2) the fact that rigidity and the considerable interval between the terminal or pilot bit 120 and the uppermost reaming element is favorable to the cutting of a straight hole, regardless of variations in hardness and in inclination of strata encountered, in that the small pilot bit is directed through such formation 125 by the superimposed reaming element, and 130

the hole cut by the pilot bit is gradually enlarged by the progressive reaming elements, each being guided by the reaming elements and the pilot bit. This feature also applies to 5 boulders, etc., in which the pilot bit might be "sprung" from its course, but would be redirected by the reaming elements after passing the boulder. The reamers would in turn gradually "mill" the boulder or such 10 similar obstacle to conform to the true course of the well hole; and (3) the fact that organizations or the general character described, or parts thereof, are capable of advantageous use not only in an efficient cutting 15 of straight holes of any desired diameter (the characteristics of the cutting teeth and the depth of cut thereof being presumably varied according to the material encountered) but in the mudding up of the 20 holes and the rectification of casings within wells,—such burnishing elements as are illustrated in Fig. 4 being optionally provided not only with rounded wall-perfected surfaces having profiles such as that shown at 25 38 but optionally also with mudding vanes 39 and/or with fluid passages or circulation spaces 40,—the upper and lower faces 41 and 42 being, in any case, clutch-like in character, in order that they may be rotated by 30 means of the general character described.

The illustrated large circulation spaces, extending inward substantially to the hubs above, below and between the teeth, permit ample external upward circulation of the 35 lubricating fluid downwardly delivered through passages 14.

I consider it distinctly preferable, in transmitting rotary motion from the shaft 11 to the described reaming elements, to provide 40 the same with cylindrical interior surfaces 43, slidably fitting upon the cylindrical exterior of said shaft, and to retain and drive the same in the described manner, rather than give such shaft a non-circular cross-sectional outline, as my preferred course obviates the expense of providing correspondingly non-circular interior surfaces within the reaming elements or the provision of a splined connection between said elements and 45 said shaft; and it accordingly facilitates the assembly or disassembly and substitution of any desired reamers, as required by conditions encountered.

Although I have herein described a single complete embodiment of my invention, suggesting various alternatives, it should be understood not only that various features thereof may be independently used but also that numerous modifications might be made 50 by those skilled in the art to which this case relates, without the slightest departure from the spirit and scope of this invention, as the same is indicated above and in the following claims.

I claim as my invention:

1. For use in a reaming and mud circulating organization of the general character described: a unitary annular reamer the end faces of which are provided with rectangular dovetailed projections and lie in planes 70 perpendicular to the axis of the reamer, the circumference of said reamer being provided with radially arranged teeth whose edges lie in a common transverse plane and in different substantially vertical planes, 75 each tooth having one flat face and one rounded face.

2. For use in a reaming and mud circulating organization of the general character described, a unitary annular element comprising: a hollow hub provided with notched faces at its ends; an integrally formed toothed section; and an integrally formed rearwardly inclined fin, of shorter radius than the teeth of said toothed section, for 80 mudding up a hole,—a plurality of like fins being symmetrically disposed and said notched faces being clutch faces.

3. For use in a reaming and mud circulating organization of the general character described, a unitary annular element comprising: a hollow hub with opposite clutch faces between which are disposed a rounded toothed section and also rearwardly inclined fins, said fins being of shorter radius than 90 the teeth of said toothed section and adapted to serve for mudding up a well hole, a plurality of like fins being symmetrically disposed in a plane distinct from that of said toothed section, and the tips of said teeth and the 95 tips of said fins being differently inclined.

4. A rotary drilling tool organization comprising: a pilot bit; a tubular body provided with means for its interposition in a rotary drill string above said pilot bit; a 105 stop member externally and rigidly secured on said body near one end thereof; symmetrical reaming elements, including hubs of substantially uniform diameter from which project integral teeth, the teeth of each upper reamer being longer than those of the next lower reamer and all of said teeth being separated by circulation spaces which extend inward substantially to said hubs, 110 said reamers being slidably assembled on said tubular body with their teeth disposed in planes substantially perpendicular to the axis thereof, and cooperating torque-transmitting means being provided on said stop member and on said hubs; and means, on the other end of said tubular body, for holding 115 said reaming elements in mutual engagement and against said stop member, to assure a transmission of torque through said hubs.

5. A drill tool organization comprising: a pilot bit; a tubular body provided with means for its interposition in a rotary drill 120

string above said bit; a stop member externally and downwardly mounted on said tubular member, said stop member having a notched upper clutch face; symmetrical 5 reaming elements of progressive upwardly increasing diameters slidably mounted on said tubular body, in planes perpendicular to the axis thereof, above said stop member,—said reaming elements comprising 10 hubs of substantially uniform diameter having cooperatively notched inter-engaging clutch faces, integrally formed and radially extending teeth separated by circulation spaces which extend inwardly substantially 15 to said hubs, and integrally formed mudding fins of less diameter than said teeth; and removable means, mounted on said tubular body, holding said elements in rigid engagement with one another and with said 20 stop.

6. A drilling tool organization comprising: a pilot bit; a tubular body provided with means for its interposition in a rotary drill string above said bit; a stop member 25 externally and downwardly mounted on said tubular body, said stop member having an upper notched clutch face; mudding elements slidably assembled on said tubular body above said member, said mudding elements comprising hubs having cooperatively 30 notched inter-engaging clutch faces and integrally formed radially extending fins, the lowermost fins being of less diameter than said pilot bit; and removable means, 35 mounted on said tubular element, for holding said mudding elements in rigid engagement relatively to said stop member.

7. A drilling tool organization comprising: a pilot bit; a tubular body provided 40 with means for its interposition in a drill string above said bit; combined reaming and mudding elements of progressive upwardly increasing diameters slidably assembled on said tubular body; a stop member, 45 provided with an upper clutch face, mounted in rigid engagement with said body and supporting said elements,—said elements including hubs which have cooperatively notched clutch faces for the transmission of 50 torque from said stop member; and means, removably mounted on said tubular body,

for holding said elements in mutual engagement, the lowermost of said elements engaging said stop member.

8. A drilling tool organization comprising: a pilot bit; symmetrical reaming elements mounted above said pilot bit and comprising hubs, of substantially uniform diameter, carrying integral teeth disposed in common transverse planes,—the upper sets 55 of teeth being longer than the lower sets of teeth, and said teeth being separated by circulation spaces which extend inward substantially to said hubs; means for securing said organization to a drill string, above 60 said pilot bit; and means for the circulation of a lubricating fluid through said organization.

9. A drilling tool organization comprising: a tubular body provided with means 70 for its interposition in a drill string; pipe burnishing elements of upwardly increasing diameters slidably assembled on said tubular body in planes perpendicular to the axis thereof,—said elements including hubs 75 which have inter-engaging clutch faces and being provided with circulation spaces which extend inward substantially to said hubs, and said tubular body being downwardly provided with a fixed stop having 80 an upper clutch face engaging the lowermost of said hub faces, and upwardly provided with removable means holding said elements and said stop in cooperating mutual engagement, to transmit torque therebetween.

10. For use in a rotary drilling organization of the general character described, an annular reamer comprising: a hub having 90 means for transmitting torque thereto; integrally formed, radially extending teeth disposed in a common plane and separated by circulation spaces which extend substantially to said hub; and integrally formed mudding fins, of less diameter than said 95 teeth, provided with faces which are backwardly inclined.

In testimony whereof, I have hereunto set my hand at Los Angeles, California, this 10th day of February, 1927.

GEORGE D. SHIELDS.
